[57] CLAIM

The ornamental design for a sanitary machine for storing and dispensing particulate ice, substantially as shown and described.

DESCRIPTION

FIG. 1 is a perspective view looking downward at the front, left side and top of a sanitary machine for storing and dispensing particulate ice, showing my new design; FIG. 2 is a front elevational view thereof; FIG. 3 is a side elevational view of the right side thereof;

FIG. 4 is a side elevational view of the left side thereof; FIG. 5 is a rear elevational view thereof; and FIG. 6 is a top plan view thereof.

The bottom is substantially flat and unornamented.
